UNITED STATES PATENT OFFICE.

ROBERT W. SCOTT, OF LEEDS POINT, NEW JERSEY, ASSIGNOR OF ONE-HALF TO LOUIS
N. D. WILLIAMS, OF OGONTZ, PENNSYLVANIA.

KNITTED FABRIC.

955,702.

Specification of Letters Patent. Patented Apr. 19, 1910.

Application filed May 26, 1909. Serial No. 498,422.

To all whom it may concern:

Be it known that I, ROBERT W. SCOTT, a citizen of the United States, residing in Leeds Point, Atlantic county, New Jersey, have invented certain Improvements in Knitted Fabrics, of which the following is a specification.

My invention relates to that class of knitted fabrics which are partly ribbed and partly plain, and present a greater number of wales in the ribbed web than in the plain web, a common instance of such fabric being found in that class of stockings in which the leg portion is composed of ribbed web and the foot portion of plain web, the ribbed web of the leg having a greater number of wales than the plain web of the foot. In the manufacture of this class of stockings the ribbed leg webs are usually knitted upon an ordinary rib knitting machine and the stitches at one end of the said ribbed leg web are then run onto the needles of an ordinary cylindrical knitting machine for knitting the foot, the excess wales of the ribbed leg web being doubled onto needles of the footing machine. Usually there are twice as many wales in the ribbed web as in the plain web, the wales of the latter forming continuations of the face wales of the ribbed web, and in running said ribbed web onto the needles of the footing machine it is necessary to transfer to said needles the stitches of the corresponding face wales of the ribbed web, and then to double onto said needles the stitches of the back wales of the web, these stitches having to be shogged laterally owing to the fact that in an ordinary ribbed web the back wales alternate with or lie midway between the face wales. The running-on operation, therefore, is one requiring considerable time and the exercise of a high degree of skill and it consequently adds materially to the expense of stockings of this class.

The object of my invention is to cheapen the production of fabrics of this type by simplifying the running-on operation, and this object I attain in the manner herein-after set forth, reference being had to the accompanying drawing, in which—

Figure 1 is a view of a stocking made in accordance with my invention, and Fig. 2 is an exaggerated view of a portion of said stocking at the point where the ribbed web joins the plain web.

The ribbed web which constitutes the leg portion of the stocking is knitted in accordance with my Letters Patent No. 899,439, dated September 22, 1908, and consists of two independent but interlocked ribbed webs, the wales of one web occupying the spaces between the wales of the other web, and the sinker wales crossing each other, as fully set forth in the specification of my said previous patent.

In Fig. 2 of the drawing the wales of one member of the duplex ribbed web *x* are shown by unshaded lines and the wales of the other member of said duplex ribbed web are shown by shaded lines. The back wales therefore lie directly behind the face wales and stitches of both wales can be applied to the needles of the footing machine simultaneously and without any shogging of the stitches of the back wales, consequently the transfer operation can be effected with the same facility as in transferring the face wales of the ordinary ribbed web, with a consequent saving of time and without the necessity of employing such highly skilled labor as is now required.

In Fig. 2 of the drawing, *a* and *b* represent the terminal stitches of the front and back wales of the ribbed web, which are simultaneously applied to the needles of the footing machine, and *c* represents the stitches of the first course of the plain web *y* which is knitted upon said footing machine needles after the application of the stitches of the ribbed web thereto.

Any desired character of foot web may be produced upon the needles of the footing machine, that which I have shown in Fig. 1 of the drawing, being a foot web with the usual seamless heel and toe pocket.

I claim:

1. A knitted fabric, partly ribbed and partly plain, the ribbed web being duplex, and the stitches of the initial course of the plain web being interknitted with wales of each member of said duplex ribbed web.

2. A knitted fabric, partly ribbed and partly plain, and composed of duplex ribbed web having the back wales in line with the face wales, and plain web having the stitches of the initial course drawn through terminal stitches of overlying wales of the ribbed web.

3. A knitted fabric, partly ribbed and partly plain, and comprising duplex ribbed

web with the back wales lying directly behind the face wales, each plain web wale being interknitted with a face wale and a back wale of the ribbed web, and said face and 5 back wales of the ribbed web being in line with the corresponding wales of the plain web.

In testimony whereof, I have signed my name to this specification, in the presence of two subscribing witnesses.

ROBERT W. SCOTT.
